UNITED STATES PATENT OFFICE.

JOHN G. OGDEN, OF COLUMBUS, OHIO, ASSIGNOR TO THE JEFFREY MANUFACTURING COMPANY, OF COLUMBUS, OHIO, A CORPORATION OF OHIO.

SINGLE-ROLL CRUSHER.

Application filed April 19, 1921. Serial No. 462,487.

To all whom it may concern:

Be it known that I, JOHN G. OGDEN, a citizen of the United States, residing at Columbus, in the county of Franklin and

5 State of Ohio, have invented certain new and useful Improvements in Single-Roll Crushers, of which the following is a specification, reference being had therein to the accompanying drawing.

10 This invention relates to coal crushing apparatus and particularly to machines known as single roll crushers.

The widely extended use of automatic stoking furnaces has created an ever increasing demand for coal crushed to a small and uniform size. When the coal crushing machines heretofore manufactured have been adjusted to produce the desired fineness of product, their capacity has usually been reduced beyond the limit of profitable operation and an unduly large proportion of the coal has been reduced to dust.

15 The common expedient by which these difficulties are avoided is the use of two crushing machines, one adapted to crush large lumps to a comparatively small size being placed above a second machine which is adapted to reduce the product of the first machine to the size required. Such a double machine is necessarily expensive and re-

20 quires a relatively powerful driving mechanism. In the patent to Whiting, No. 1,045,-763, is disclosed a machine comprising a roll rotating adjacent a stationary breaking plate wherein the surface of the roll is thickly set with a relatively large number of relatively small crushing teeth and a much smaller number of relatively long hook shaped teeth, the hook shaped teeth serving

25 to draw the larger fragments of the coal down into the machine to be crushed, and the small crushing teeth to crush it to the desired size. A smooth breaker plate is normally supported in such manner that there shall be only a running clearance between its lower part and the top of the crusher teeth. In order that the hook shaped teeth may pass, grooves are provided in the breaker plate, and the proportions of the teeth and grooves are such that there shall be only the necessary running clearance and

the grooves shall be no wider than the greatest desired dimension of the fragments of the product.

Such machines have proven satisfactory 55 within certain limits, but it has been found impossible to reduce the thickness of the hook shaped teeth beyond certain limits in order that they may possess sufficient strength for successful operation, and the 60 width of the slots through which the hook shaped teeth pass is, in practice, the limiting dimension of the maximum fragments of the product.

It is the principal object of this invention to provide a machine of relatively large capacity which shall be adapted to receive run of mine coal, including both large and small fragments, and, by a single operation, 65 reduce it uniformly to the small size suitable for modern stoker furnaces.

The means by which I attain this object are fully set forth in the following specification and illustrated in the accompanying drawings of which—

70 Fig. 1 is a side elevation of the preferred embodiment of my invention.

Fig. 2 is a sectional view taken along the central transverse vertical plane of the machine which coincides with the line II—II 80 of Fig. 4.

Fig. 3 is a transverse sectional view taken along a vertical plane between the end of the crushing roll and the frame of the machine and which coincides with the line III—III 85 of Fig. 4.

Fig. 4 is a longitudinal sectional view taken along the line IV—IV of Fig. 2.

Like numerals refer to similar parts in the several figures.

90 Referring to the drawings the numerals 1—1 indicate the end frames upon which the crushing mechanism is mounted. Journal bearings 2 and 3 are formed in these end frames and in these journal bearings are 95 mounted the shaft 4 of the crushing roll and the counter-shaft 5. These journal bearings are provided with the usual removable caps so that the machine may be easily taken apart when so desired. A hub 6 provided 100 with radial wings 7 is keyed to one end of the shaft 5 and upon this hub is mounted a

5 pulley wheel 8 which is rotatively connected thereto by means of the pins 9 which pass through the wings 7 and the arms of the pulley 8. These pins 9 are made of hard wood or other suitable material and their cross section is such that in case of a sudden over-load being thrown upon the machine they will shear, thus disconnecting the shaft 5 from the driving element. This provides 10 a safety device such as will eliminate any possible danger of the machine being broken or its bearings injured by the sudden application of an excessive load.

15 Mounted on the shaft 4 is the crushing roll 10 to the periphery of which is secured a series of segmental plates 11 upon the outer surface of which are formed a relatively large number of crushing teeth 12 of such dimensions and so spaced that the distance 20 between any two contiguous teeth shall be no greater than the greatest permissible dimension of the fragments of the desired product.

25 A breaker plate 13 is pivoted on the shaft 14 at the upper front part of the machine, and is so disposed that it and the roll form opposite downwardly converging walls of a passage through which the coal moves to the final crushing points at the lower side of the breaker plate. An arcuate slot 15 is formed 30 intermediate the ends of the breaker plate through which extends a tie rod 16 which holds the side frames 1 in spaced relation and at the same time affords a stop and guide when the breaker plate swings about the shaft 14. A shaft 17 extends through the breaker plate 13 below the arcuate slot 15 and has mounted upon its ends two eye bolts 18 which extend rearwardly through the lugs 19 upon the side frames 1. Springs 20 are placed upon the extremities of the bolts 18 outside the lugs 19 and are retained in place by the nuts 21 by the adjustment of which the tension of the spring 20 may be regulated. This provides a cushioning of 35 the breaker plate so that when an unusually hard piece of material passes between the roll and the breaker plate instead of breaking the teeth of the roll or jamming the machine, the breaker plate will be swung back as far as necessary, depending upon 40 the tension of the springs 20.

45 It has been found that when such a crushing roll is provided only with small crushing teeth appropriate to the production of finely crushed coal, that the larger lumps will roll on the top of the crushing roll and not be drawn down into the machine to be crushed. To overcome this difficulty I have provided 50 radially elongated teeth 22 adapted to engage these large fragments of coal and drag them down into the machine to be crushed. These teeth 22 are slidably mounted in apertures 23 of the crushing roll and are secured to the outer surface of supporting bars 24 55 which extend longitudinally of the roll and

are slidable in radially extending guide ways 25 formed in the spokes 26 of the crusher roll. Mounted upon the ends of the bar 24 are rollers 27 adapted to travel upon the surfaces of the cams 28 and 29 formed 70 in the end frames 1 of the machine. The cams 28 and 29 are of such form that, at the upper part of their path of rotation, the elongated teeth 22 will be thrust outwardly of the roll to engage the lumps of coal and 75 drag them downwardly in the machine to be crushed against the breaker plate 13, and at the lower part of their path of travel the teeth 22 will be withdrawn into the roll so as to avoid contact with the breaker plate 13. 80 The teeth 22 it will be seen are positively operated both as they are projected, and as they are withdrawn, so that they will move to and from their extreme positions with certainty, and danger of such teeth being 85 broken, or the machine injured, or the teeth failing to perform their proper functions, because of inopportune projection or withdrawal, is eliminated.

89 By the arrangement of parts just described the elongated teeth 22 are available at the upper part of the tapering passage to engage the material to be crushed and drag it downwardly to the ultimate crushing point at which point said feeding teeth are withdrawn into the roll to prevent contact with the breaker plate, thereby permitting such adjustment of the breaker plate relative to the crusher roll that there shall be no space available for the passage of material of 100 greater dimensions than the desired fragments of the product.

95 Another advantageous feature of construction and arrangement of parts is that the hopper chamber is positioned remote from the center, vertically, of the hopper, and communicates with the wide tapering passage between the breaker plate and the roll; while the casing wall on the other side of the roll is concentric with it and relatively close 110 to the circles of rotation of the teeth. The reciprocating teeth act to check the downward passage of any material between the roll and this curved casing section. These teeth begin to project outward after crossing the vertical plane of the axis and reach their outermost points while they are traveling through the hopper chamber and through the upper wider part of the tapering passage between the breaker plate and the 115 roll.

120 What I claim is:

125 1. In an apparatus for crushing coal, the combination with a frame, of a crushing roll rotatably mounted in the frame, a breaker plate mounted in the frame at one side of said roll and forming therewith opposite downwardly converging walls between which the coal passes downwardly 130 to the final crushing points, relatively small

crushing teeth formed upon the surface of the roll and uniformly spaced to crush the coal to the desired degree of fineness, a plurality of transversely disposed feeding teeth projecting radially of the crushing roll and adapted to engage the material to be crushed to draw it downwardly into the tapering passage, teeth supporting bars lying within the roll and positively acting means to withdraw said bars and feeding teeth into said roll to avoid their contact with the breaker plate at the final crushing points.

2. In an apparatus for crushing coal, the combination with a frame, of a crushing roll rotatably mounted in the frame, a breaker plate mounted in the frame at one side of said roll and forming therewith opposite downwardly converging walls between which the coal passes downwardly to the final crushing points, relatively small crushing teeth formed on the surface of the roll and uniformly spaced to crush the coal to the desired degree of fineness, apertures in said roll, a plurality of transversely disposed feeding teeth radially movable in said apertures, teeth supporting bars lying within the roll and positively acting means to move said bars and teeth outwardly to engage the material to be crushed to draw it downwardly into the tapering passage and to withdraw said feeding teeth into said roll to avoid contact with the breaker plate at the final crushing points.

3. In an apparatus for crushing coal, the combination with a frame, of a crushing roll rotatably mounted in the frame, a breaker plate mounted in the frame at one side of the roll and forming therewith opposite downwardly converging walls between which the coal passes downwardly to the final crushing points, relatively small crushing teeth formed upon the surface of the roll and uniformly spaced to crush the coal to the desired degree of fineness, apertures in said roll, a plurality of transversely disposed feeding teeth extending radially through said apertures and attached to supporting bars which extend longitudinally and inside of said roll, and means engaging said bars positively to move said feeding teeth outwardly to engage the material to be crushed to draw it downwardly into the tapering passage and positively to draw said feeding teeth into the roll to avoid contact with the breaker plate at the final crushing points.

4. In an apparatus for crushing coal, the combination with a frame, of a crushing roll rotatably mounted in the frame, a breaker plate mounted in the frame at one side of said roll and forming therewith opposite downwardly converging walls between which the coal passes downwardly to the final crushing points, relatively small crushing teeth formed upon the surface of the roll and uniformly spaced to crush the coal

to the desired degree of fineness, apertures in said roll, a plurality of transversely disposed feeding teeth extending radially through said apertures, teeth supporting bars extending longitudinally and inside of the roll, and guide ways formed in the end frames and engaging the ends of said supporting bars positively to move said feeding teeth outwardly to engage the material to be crushed to draw it downwardly into the tapering passage and positively to withdraw said feeding teeth into said roll to avoid contact with the breaker plate at the final crushing points.

5. The combination of the roll having a plurality of transversely and radially disposed reciprocating feeding and crushing teeth, means positively to project and withdraw said teeth at predetermined intervals, the breast plate on one side of the roll, and the casing having a feeding hopper and a closure wall on the other side of the roll approximately concentric therewith and having its inner surface relatively close to the circles of rotation of the teeth, whereby the passageway between the roll and said wall section is closed against downward travel of material, said breast plate being arranged to provide a passageway from the hopper which tapers downward to the circles of rotation of the teeth.

6. The combination of the roll having a plurality of transversely and radially disposed reciprocating teeth, means positively to project and withdraw said teeth at predetermined intervals the hopper arranged to deliver material to one side of the roll, the yielding breaker plate at one side of the roll, the casing wall approximately concentric with the roll and arranged relatively close to the teeth thereon, the reciprocating teeth being arranged to project farthest from the center of the roll when they are traveling through the lower part of the hopper and the upper part of said tapering passageway.

7. In a crushing machine, the combination of a rotary crushing roll having teeth each projecting at a fixed angle from the exterior thereof, a breaker plate arranged in operative relation to said roll, the space between the roll and the breaker plate forming a hopper for the materials to be crushed, means to rotate said roll, and instrumentalities operated automatically by the rotation of the roll and revolving therewith to in effect merely push the teeth outward and to positively pull the teeth inward, when the roll is operated, so that the angle of the teeth is maintained, whereby said crushing roll and said teeth have relative movement to prevent the teeth from striking said plate.

8. A structure as specified in claim 1, said instrumentalities comprising a plurality of eccentrics serving automatically to retract said teeth while passing the lower end of said

plate and to automatically present said teeth in operative position before they again enter the hopper at the top thereof.

9. A structure as specified in claim 1, said crushing roll having other teeth which are shorter than said first mentioned teeth, the latter being controlled by said instrumentalities to alternately push them outward and draw them into the roll.
10. A structure as specified in claim 1, said teeth being arranged in rows, and other teeth disposed between said rows on the roll, said last mentioned teeth being shorter than said first mentioned teeth.
11. A structure as specified in claim 1, said breaker plate presenting a smooth and

plain surface to said roll, inasmuch as said relative movement obviates the necessity of forming any clearance in said plate for the teeth.

12. In a crushing machine, the combination of revolving teeth, means to revolve the teeth, means cooperating with said teeth to produce the desired crushing action, and means including revolving elements to automatically control said teeth, whereby each tooth has only endwise movement relatively to the revolving means, to alternately present them in operative position and retract them during the revolving motion thereof.

In testimony whereof, I affix my signature.

JOHN G. OGDEN,
